TAPE LADDER FOR VENETIAN BLINDS

George C. Runge, Chicago, Ill., assignor to E. L. Mansur Company, Chicago, Ill., a corporation of Illinois

Application June 22, 1935, Serial No. 27,884

5 Claims. (Cl. 156—17)

The object of the present invention is to provide an improved ladder tape for use in the construction of Venetian blinds.

This new ladder tape—as compared to the so-called "English" ladder tape which has been used almost without exception in all Venetian blinds made during the past forty or fifty years—presents a much finer appearance, is capable of receiving a woven-in design on its face band, will 5 fold into uniform pleats without irregular buckling or creeping when the slats are raised, is considerably less expensive to produce, requires no cutting to complete its manufacture, contains no loose ends, and can be used to hold the slats down 10 as well as support them, if desired.

The English type tape, which is still made substantially in accordance with the disclosure in British Patent No. 4972 of 1888, contains staggered cross webs which are woven at the same 15 time as the face and rear bands. Because of its construction, the weaving of an ornamental design into the bands is impractical, and where ornamentation has been insisted on the same has been obtained by the expensive and none too satisfactory expedient of tacking separately woven 20 bands to the face bands in such a way as to conceal the latter. Furthermore, the cutting operation required in order to open up the English tape after it has been woven is not only expensive 25 but is likely to leave either frayed ends or else incisions in the face bands unless the cutting is done slowly and with great care. Moreover, the staggered arrangement of the cross webs, combined 30 with the absence of any transverse stiffening or reinforcing means has the tendency sometimes not only of causing the bands to buckle 35 and pleat irregularly in folding but also of producing a creeping effect toward one side or the other which is quite objectionable when the blind 40 is lowered.

The new ladder tape can be made on a simple three-shuttle loom, with two of the shuttles carrying the fillers and the third carrying the material for the cross members, which material is 45 preferably in the form of a round braided cord, although it may be in some other form. While the tape is being woven, an ornamental design may be simultaneously worked into the face band. The cord, which has considerable strength and 50 body, is carried back and forth to form supports for the slats adjacent both sides of the bands, and intermediate the levels for the slats the cords are woven into the rear band transversely of the latter at short regular intervals, to give the effect 55 of stiffening battens, the short intervening por-

tions of the cord between these transverse reinforcing ribs being specially arranged in small free loops which in no way interfere with the even folding insured by the presence of the rung-like stiffening ribs but on the other hand add appreciably to the appearance of the tape as a whole and require no cutting.

Shortly after the English type tape has developed, an attempt was made to devise a tape with double strings for supporting the slats, as 10 evidenced by the showing in Austrian Patent No. 416 of 1899, but the tape of that patent, like the English tape, contemplated the cutting away of material which if left would be not only unsightly but in the way, and while it could be produced on 15 a three-shuttle loom its structure was impractical and it never succeeded in making any impression in the practical development of the art.

While the foregoing statements are indicative in a general way of the nature of the present 20 invention, other objects and advantages will be apparent to those skilled in the art upon a full understanding of the construction of the improved tape and the method employed in its manufacture.

A preferred embodiment of the invention is 25 presented herein for the purpose of exemplification, together with a few illustrative modifications, but it will of course be appreciated that the invention is susceptible of embodiment in still 30 other structurally modified forms coming equally within the scope of the appended claims.

In the accompanying drawings:

Figs. 1 and 2 are, respectively, fragmentary 35 front and rear perspective views of the new ladder tape, showing a few slats in position in the tape;

Fig. 3 is a perspective view of an ordinary three-shuttle loom, showing the way in which the tape is woven in a flattened out position;

Fig. 4 is another fragmentary front perspective view of the tape illustrated in Figs. 1 and 2, showing the way in which the connecting portions of the cord can be used to hold the slats down as well as support them;

Fig. 5 is a similar view of a modified form of the tape, showing the supporting portions of the cord crossed;

Fig. 6 is a fragmentary rear perspective view of the tape illustrated in Fig. 5, in this case 50 showing the way in which the crossed cord formation can be used to hold the slats down as well as support them; and

Figs. 7 and 8 are, respectively, fragmentary front and rear perspective views of another mod- 55

ified form of the tape in which the cord material for the slat-supporting members is also used as the filler for the rear band, permitting the tape to be woven on a two-shuttle loom.

5 Referring first to Figs. 1 and 2, it will be observed that the improved tape includes a face band 10 and a rear band 11. These bands are connected together at regular intervals by a continuous braided cord 12. The two bands are 10 woven at the time that the cord is applied, and the latter is woven into the bands at certain transverse lines of connection.

15 The ladder tape may be woven on an ordinary three-shuttle loom of the type shown fragmentarily in Fig. 3, the shuttles 13 and 14 being used to carry the filler threads 15 and 16, and the shuttle 17 being used for the cord 12. The tape is woven with the bands 10 and 11 arranged in the same plane, in flat parallel outspread relation, with the free cross-connecting portions 19 and 20 of the cord 12 controlled as to length by the spacing of the bands as determined by the arrangement of the two sets of warp threads 21 in the reed 22.

25 At regular intervals during the weaving of the bands 10 and 11 the cord 12 on the shuttle 17 is passed through the shed of the warp threads of the band 11, causing the cord to be woven transversely into that band from point *a* to point *b*. From point *b* the cord is then transferred free of the warp threads of the band 11 to the band 10 at *c*, where it is passed through the shed of the warp threads of the band 10 and woven into that band from *c* to *d*. From *d* the cord is 30 passed clear of the sheds of the warp threads of both bands back to the band 11 at *e*, which point is the same as *a*. The free sections from *b* to *c* and from *d* to *e* constitute the slat-supporting portions 19 and 20 of the cord. From *e* the cord 40 is woven into the band 11 alongside the already woven-in section *a*—*b* to *f*, which point is the same as *b*. Then from *f* the cord leaves the rear surface of the band 11 in a small loop 23 and enters the band 11 again at *g*, where it is woven 45 into the band crosswise of the latter from *g* to *h*. Then from *h* the cord leaves the band 11 again in a small loop 24 and enters it at *i*, being woven in again from *i* to *j*. Then after another loop it is woven in again from *k* to *l*. From *l* the cord 50 is carried in still another loop to the next starting point *a'*, which point corresponds to the first described point *a* at the next slat level, where the process is repeated.

55 In this way, the cord 12 is securely woven into the bands 10 and 11, with two spaced parallel portions 19 and 20 of the cord arranged at each slat level, and with a plurality of transverse stiffening ribs 25 built into the rear band not only at the separated levels of the portions 19 and 20 60 but at several equally spaced intermediate locations. As a result of this construction, the weight of the slats 26 will exert an equal pull on both sides of the band at the same time, and the stiffening ribs in the rear band 10 (which is the 65 band ordinarily more exposed to the elements) will prevent that band from curling or otherwise getting out of shape and yet will allow it to fold not only just as easily but even more uniformly. The lifting cord 27 for the blind passes between 70 the slat-supporting portions 19 and 20 of the cord through transversely elongated slots in the slats, as is usual in Venetian blind structures.

75 The ladder tape which is shown in Fig. 4 is the same as that shown in Figs. 1 and 2, but the arrangement of the slats with respect to the sup-

porting members 19 and 20 is different. As will be observed, the slat is placed on top of the cord portion 19 under the cord portion 20, with the result that the slat is held down as well as supported by the cord portions.

5 In the modification which is shown in Fig. 5, the slat-supporting cord portions 29 and 30 are crossed at the location of each slat. In all other respects the tape shown in this view is the same as the previously described tape. In Fig. 6 the tape which was illustrated in Fig. 5 is again shown but in this view the slat is placed on top of the cord portion 29 and beneath the cord portion 30.

10 In the modification which is shown in Figs. 7 and 8 the ladder tape is produced on a two-shuttle loom, with the braided cord 31 which is used for the slat-supporting members and the transverse stiffening members also used as the filler material 32 for the rear band 33. This construction, like the ones previously described, gives the 15 desired transverse reinforcement to the rear band while retaining the longitudinal flexibility of the latter.

20 Aside from the improved folding characteristics of this new tape, the method of weaving employed in its fabrication permits of the use of any desired color combination. For instance, the inside or face bands may be of a different color in each of several rooms so as to harmonize with the color schemes in those rooms while the outside or rear bands may be all of the same color 25 in all of the rooms in order to give a uniform appearance to the tapes of the blinds from the outside of the building, which color treatment is not possible with the commonly used English type 30 of tape.

35 I claim:

1. In a tape ladder for Venetian blinds, the combination with the face and rear bands of the 40 tape, of slat-supporting members connecting the bands at regular intervals, and transverse stiffening members in one of the bands intermediate the locations of the slat-supporting members.

2. In a tape ladder for Venetian blinds, the combination with the face and rear bands of the 45 tape, of a continuous cord which is woven first into one band and then into the other to provide slat-supporting members at regular intervals, and transverse stiffening members in one of the bands intermediate the locations of the slat-supporting 50 members.

3. In a tape ladder for Venetian blinds, the combination with the face and rear bands of the 55 tape, of a continuous cord which is woven first into one band and then into the other to provide slat-supporting members at regular intervals between corresponding sides of the bands and transverse stiffening members in the rear band intermediate the locations of the slat-supporting members.

4. A method of producing tape ladder for Venetian blinds, which consists in weaving both of the side bands simultaneously in a loom with the bands arranged side by side on one level, working into both bands as they are being formed a continuous cord which is at intervals transferred laterally from one band to the other to form slat-supporting members between the bands and transverse stiffening members in the rear band 70 intermediate the locations of the slat-supporting members.

5. A method of producing tape ladder for Venetian blinds, which consists in weaving both of the side bands simultaneously in a loom with the 75

bands arranged side by side on one level, working into both bands as they are being formed a continuous cord which is at intervals transferred laterally from one band to the other to form slat-supporting members between the bands and transverse stiffening members in the rear band intermediate the locations of the slat-supporting

members, with the portions of the cord between the stiffening members and the slat-supporting members arranged in small loops which alternate in location from one side of the rear band to the other side of that band.
